VOTE COUNTING MACHINE

John H. Randolph, Great Bend, Kans.

Application October 21, 1939, Serial No. 300,609

1 Claim. (Cl. 235—56)

My invention relates to an improvement in machines for counting votes.

The object of the invention is to correctly count the votes and do it quickly and easily.

A further object is to provide a machine of the kind mentioned which may be driven either by hand or power.

A still further object is to provide a machine of the kind mentioned that is simple and inexpensive to make and positive in its action.

These and other objects will be more fully explained as this description progresses.

Now referring to the accompanying drawings, Fig. 1 is a plan view of the vote counting machine.

Fig. 2 is an end view of the vote counting machine.

Fig. 3 is a side view of the vote counting machine.

Fig. 4 is a longitudinal sectional view of the vote counting machine, the view being taken along the line IV—IV in Fig. 1, looking in the direction of the arrows.

Fig. 5 is an enlarged detail sectional view of a portion of the rollers and mechanisms carried thereby for counting the votes.

Fig. 6 is a detail side view of a portion of the machine and showing the power drive hook up, of the machine.

Fig. 7 is a plan view of the ballot card to be used with my improved vote counting machine.

Similar numerals of reference designate the same parts throughout the several figures of the drawings.

In the drawings is shown my improved vote counting machine in which is included a rectangular shaped frame portion which has end cross members 10 and 11, and duplicate shaped side members A and B. Each of the side members A and B have an upwardly projecting portion 12 in which is a vertically positioned slot 13. In the slot 13 is positioned blocks 14 and 15 in which are bearings for axle shafts 16 and 17 on which is mounted a register carrying drum 18 and a register operating drum 19 in such a manner that the register operating drum 19 rests on the register carrying drum 18.

On each of the side frames A and B is formed a rectangular frame C having inwardly turned ledges 20 at the bottom thereof on which the ballot cards 21 are supported in such a manner that the bottom card lies on a plane that will pass tangentially between the two rolls 18 and 19. The front wall 22 of the ballot rack C lacks a little bit of coming down as far as the ledges

20 so as to leave a long narrow opening 23 at the bottom of the ballot card holder frame through which the ballots may be fed from the bottom of the pile of ballots 21, one at a time, between the rolls 18 and 19 for vote counting as will later be described.

At the left hand end of the machine is formed a receiving chamber 24 in which the cards 21 are received as they are discharged from between the rollers 18 and 19.

The axle is provided with cranks 25 and 25a, the outer ends of which are provided with pins on which one end of the connecting rods 26 and 26a are connected and the other ends of the connecting rods 26 and 26a are connected at 27 and 27a to the outer ends of a feed bar 28 which is slidably positioned in the slots 29. In the frame members A and B and below the ledges 20, on the feed bar 28 is a raised portion 29 that is high enough to slide between the ledges 20 and catch the bottom card 21a and move it forward through the slot 23 and feed it between the two rollers 19 and 18, which, as they are rolled together, will discharge the card 21a therebetween into the receiving chamber 24 as indicated by the arrows 30.

The ballot consists of a card board having spaces 31 marked thereon in which the name of the office and the name of the candidate for that office is printed. The voting is done by punching holes 32 in the card in the space of the candidate for whom the vote is cast. These holes are punched by a voting machine or by hand, according to the system of voting in vogue at the place of voting.

On the crank 25 is an outwardly extending pin on which is revolvably mounted a crank handle 33, by which the roll 18 is revolved.

Also on the shaft 17 is rigidly mounted a pulley 34 that is driven by a belt 35 that is driven by a small pulley 36 which is rigidly attached to a pulley 37 that is driven by a belt 38 which is driven by a small pulley 39 that is rigidly mounted on the revolvable shaft of an electric motor 40. The pulley 36—37 being revolvably mounted on the outer end of the shaft 16. This provides a power drive for the machine which may be used instead of turning the rolls by hand by the handle 33.

Mounted on the roll 18 is a plurality of rows of registers as indicated at 41, each register 41 having an operating lever 42 that is pivotally connected with an operating plunger 43 that is slidably mounted in a socket 44 and the end of the plunger 43 is normally positioned about flush

with the face of the roll 18, said position being maintained by the pressure of a small leaf spring 45 on the operating lever 42 which rests on the pin 46 that is mounted on the case of the register 41. The spring 45 is also rigidly mounted on the case of the register 41.

The roll 19 is provided with a plurality of rows of depressible pin elements 47 that are positioned in alignment with the rows of plunger elements 43.

The pins 47 project through holes in the roll 19 and project beyond the face of the roll 19. The inner end of the pins 47 pass through holes in a guide ring 48 that is carried on the roll 19 and as a part thereof. On each of the pins 47 is a stop element 49 that rests against the under side of the material of the roll 19 and functions to limit the outward movement of the pin 47. Around each pin 47 is a helical spring 50 that is under compression between the stop 49 on the pin 47 and the guide ring 48 so that the spring 50 urges the outward movement of the pin 47. The spring 50 is a stronger spring than the spring 45 so that as the rolls 18 and 19 roll together the pins 47 will engage the plungers 43 and push them upward so as to raise the operating levers 42 and thereby operate the register 41.

Now if a cardboard is rolled between the rolls 18 and 19, the cardboard will function to press the pins 47 downwardly as indicated at 47a so as to prevent contact of the pins 47 with the plungers 43, but if there be a hole 32 in the card the pin 47b will pass through the hole and contact the plunger 43 to raise the plunger 43 and operate the register 41.

In Figs. 1 and 2 the plungers 43 are shown as being in line with the face of the registers 41. This is done so as to make the plungers 43 coincide with the holes 32 in the ballot card 21 as shown in Fig. 7. It will be understood that if in voting the ballot, the holes 32 were placed along the margin of the voting space instead of the middle as shown, the machine would be built with the plungers 43 between the rows of registers instead of in line with the rows of registers so that the plungers 43 would again coincide with the row of holes 32 as will readily be understood.

The operation of the device is as follows: After the ballots have been voted by having a hole 32 punched in the space containing the name of the candidate for whom the vote is cast, the pile of ballots 21 are placed in the tray between the walls C and the front wall 22, whereupon the machine is set in motion, either by turning the handle 33 or being driven by the motor 40, whereupon the rolls 18 and 19 will roll together and the links 26 and 26a will move the

notched feed plate 28 so that the notch 29 will catch the rear edge of the card 21a and feed it through the slot 23 and between the rolls 18 and 19, and as the card is rolled between the rolls 18 and 19, if there be a hole therein where a vote was cast, one of the rods such as 47b will pass through the hole in the card and engage the plunger 43 to move it upwardly, and thereby operate the register 41 to register the vote that was cast. If there is no hole in the card 21a, as the card is rolled between the rolls 18 and 19, the card board will depress the rods at 47 as shown at 47a and will prevent the rods 47 from engaging the rod 43 and therefore no vote will be registered by the register 41.

It is obvious that the cards being fed between the rolls 18 and 19 by the feeding mechanism 26-26a-28, each card is fed between the rolls 18 and 19 at precisely the same relative position to the roll 18, therefore each meter counts only the vote for its respective candidate.

It will be understood that a small number of blank cards may be put in both the top and bottom in the feeding tray so as to not count any extra votes before the regular ballot cards start through the machine. As the cards 21a are rolled between the rolls 18 and 19, they are discharged therefrom into the receiving tray as at 21b.

Such modifications may be employed as lie within the scope of the appended claim without departing from the spirit and intention of the invention. Having fully described my invention, I claim:

35 In a machine for counting votes designated in a ballot card by perforations in the card and in candidate name carrying spaces defined on said card; a drum having a plurality of registers therein, one register for each candidate space defined on said ballot card, each register having means exposed at the face of the register carrying drum for actuating the register, a second drum, said second drum having yieldable means therein that is engageable with the register actuating means for the movement thereof to register a count on the register, said ballot card being passable between said drums and functioning to prevent engagement of the yieldable means in the second said drum with the register actuating means in the first said drum except in such places as the ballot card is perforated, said perforations in the ballot card functioning to permit the passage of the yieldable means therethrough to engage and move the register actuating means to register a count on each register respective to each perforation in the ballot card.

JOHN H. RANDOLPH
